INDUCTION HEATING COIL

Homer G. Anderson, Newtonville, Mass., assignor
to Raytheon Production Corporation, Newton,
Mass., a corporation of Delaware

Application January 29, 1935, Serial No. 3,930

4 Claims. (Cl. 219—47)

This invention relates to induction heating coils, and more particularly to such coils for heating elements of electrical space discharge devices during the manufacture thereof.

5 An object of this invention is to provide a heating coil of the type described which can heat flat plate elements, placed in substantially a vertical plane of electrical space discharge devices more effectively than has heretofore been possible.

10 A further object is to produce such a device which is simple and rugged in construction.

The foregoing and other objects of the invention will be best understood from the following description of an exemplification thereof, reference being had to the accompanying drawing, wherein:

Fig. 1 is a side view of my novel heating coil, with a portion of the lining thereof broken away to show a tube in place therein;

20 Fig. 2 is a cross-section taken along line 2—2 of Fig. 1; and

Fig. 3 is a side view of the coil shown in Fig. 1 at right angles to the showing of Fig. 1 and in which the lining member has been removed.

25 In the manufacture of electrical space discharge devices, the metallic elements placed therein are usually freed from occluded gases by heating said elements to a comparatively high temperature while the tube in which they are placed is connected to a vacuum pump. This heating can conveniently be carried out by sub-

30 jecting said metallic elements to a magnetic field varying at a comparatively high frequency and passing through said metallic elements. In order to produce such a field, coils wound in the shape of a solenoid have been used. With coils of this type it has been difficult to heat flat plate-

35 like elements within the tube, particularly when such plates were located in a vertical plane within said tube. I have found that by constructing a coil in accordance with my present invention,

40 difficulties of this nature have been eliminated and tube elements of the type described can be readily and effectively heated to the necessary temperature.

45 In the drawing I have shown a coil 1 consisting of a plurality of turns 2, preferably of hollow conductive tubing. These coils are made of material which is both a good electrical and a good heat conductor, such as, for example, copper. The major length of each of the turns 2 is located in a vertical plane. At the lower end of the coil 1 the turns 2 are separated into substantially two equal groups. Each group is then bent outwardly so that the ends 3 and 4 thereof are located in

a plane substantially at right angles to the vertical plane in which the major portion of each turn lies. In order to insulate each turn 2 from each other turn, I preferably interpose strips of insulating material 5 between each adjacent turn. 5 These strips of insulating material 5 are sufficiently flexible so that when the ends 3 and 4 of the coil 1 are bent outwardly, the insulation 5 is likewise bent. In order to retain the coil in the proper shape and prevent separating of the individual turns thereof, I prefer to wind around the various legs of the coil 1, insulating tape 6. This insulating tape is shown on but a portion of the coil of Fig. 1 in order to show the underlying structure of said coil.

10 By bending the ends 3 and 4 of the turns 2 outwardly in the manner as indicated above, there is provided an opening at the lower end of the coil 1 lying in substantially a horizontal plane. Within this opening I insert a tubular insulating sleeve 7 which prevents any member inserted within the coil 1 from coming in contact with the sides of said coil. The two ends 8 and 10 of the coil 1 are adapted to be connected by means of electrical conductors 11 and 11' to some suitable source of high-frequency current. In order to cool the coil, the terminal portions 8 and 10 may be provided with threaded connections 13 and 14 so as to connect the coil 1 to a source of cooling water, not shown.

15 When the coil 1 is energized in the manner indicated, an electrical space discharge device 15 having a glass envelope 16 and a flat plate-like metallic member 17 therein may be inserted within the sleeve 7 in such a manner that the plane 33 of the plate 17 is substantially in the plane of the vertical portion of the individual turns 2. This plane is substantially the one shown in Fig. 3. Due to the arrangement of the coil such as I have indicated, the magnetic field created thereby extends substantially at right angles to the plane shown in Fig. 3, and therefore the major portion of this field passes directly through the plate member 17 at right angles thereto. This arrangement produces a maximum effectiveness 20 of heating.

25 This invention is not limited to the particular details of construction and materials as described above as many equivalents will suggest themselves to those skilled in the art. It is accordingly desired that the appended claims be given a broad interpretation commensurate with the scope of the invention within the art.

What is claimed is:

30 1. An induction heating coil comprising a plu-

rality of turns electrically connected in series and lying in parallel planes, each coil having a corresponding portion flared outwardly to lie in a plane at an angle to said parallel planes 5 whereby a pocket is formed within the turns of the coil for receiving an object extended perpendicularly to the longitudinal axis of said coil.

2. An induction heating coil comprising a plurality of turns electrically connected in series 10 and lying in parallel planes, each coil having a portion flared outwardly to lie in a plane substantially perpendicular to said parallel planes whereby a pocket is formed within the turns of the coil for receiving an object extended per- 15 pendicularly to the longitudinal axis of said coil.

3. An induction heating coil comprising a plurality of turns electrically connected in series and having an elongated transverse axis, the

turns being formed to have one end flared outwardly from the plane of the main portion of the turns to lie in a plane substantially perpendicular to the plane of the main portion of the turns whereby a pocket is formed within the 5 coil.

4. An induction heating coil comprising a plurality of turns electrically connected in series and having an elongated transverse axis, some 10 of said turns having a portion at one end flared outwardly in one direction and the other turns having a portion at the same end flared outwardly in the opposite direction so that said flared portions are oppositely disposed and provide an opening to receive within said coil an 15 object extended perpendicularly to the longitudinal axis of said coil.

HOMER G. ANDERSON.
